OVERHEAD DOOR

Daniel Gallagher and Frank W. Riverman,
Portland, Oreg.

Application November 6, 1939, Serial No. 303,069

7 Claims. (Cl. 20—19)

This invention relates to overhead doors, and has particular reference to an improvement in overhead doors of the rigid type which are adapted to open upwardly and assume a substantially horizontal overhead position when fully opened.

In general, the object of the present invention is to provide an improved overhead door for garages and the like, the door and its operating mechanism being of inexpensive, sturdy construction, and wherein the weight of the door is counterbalanced so that little manual effort is required in the opening and closing thereof.

A particular object of the present invention is to provide an improved operating mechanism for overhead doors of the rigid type, which will hold the door either in completely opened or completely closed positions with sufficient force to prevent rattling, and which will counterbalance the weight of the door when the latter is being closed or opened.

A further object is to provide an improved bearing and lever arm for the door operating mechanism which will reduce wear and maintain the door in proper alignment at all times.

These and other objects of the invention will become apparent as the description proceeds in connection with the accompanying drawings, in which:

Figures 1 and 2 are sectional views showing the door in opened and closed positions, respectively.

Figure 3 is a sectional view showing the door in a partly opened position.

Figure 4 is a fragmentary sectional view taken on the line 4—4 of Figure 1 with the door in opened position.

Figure 5 is a fragmentary sectional view taken as Figure 4, but with the door in closed position.

Figure 6 is a fragmentary enlarged view of a bearing and lever arm with a portion of the bearing broken away.

Figure 7 is a perspective view showing the door construction.

In the preferred embodiment, the door and door operating mechanism forming the subject matter of this invention are shown as applied to a building such as a garage, or the like, having a door frame 1. The door 2 is rigid, having stiles or rails 2A and panels 2B.

Extending rearwardly from the top of the door frame and at each side thereof are the tracks or guides 3. In the preferred embodiment these tracks are illustrated as sloping slightly downwardly away from the door frame. Brackets 4 on the upper corners of the door 2 carry rollers 5

adapted to run on the tracks 3. The rollers 5 carry the upper end of the door in its movement from opened position to closed position, and vice versa.

- 5 A bearing 6 is mounted, preferably on the door frame, at each side of the door at a height intermediate the top and bottom of the frame. The bearing 6 is illustrated as bolted or otherwise securely fastened to the inside of the frame 1. Each bearing 6 carries a pivoted lever arm 7. The lever arm 7 has three parts preferably formed integrally from a single steel rod of a size suitable for a proper fit in the bearing 6. One arm of the lever 7 is provided with an extension 8 directed at right angles to the central portion contained within the bearing 6. The other end 9 of lever 7 is directed substantially opposite from the extension 8 and is also at right angles with the central portion or journal contained within the bearing 6. The extensions 8 are pivotally attached to the respective lower corners of the door 2 by means of brackets 10. If desired, provision may be made for adjusting the combined length of lever arm 7 and extension 8 by 15 making 8 of a tubular construction to fit over the lever 7. The lever 7 and the extension 8 may be integrally united, with the lever 7 extending a sufficient distance out of the tube 8 to give the desired length. This construction admits of 20 greater flexibility for application to doors of different sizes.

It is important to note that the two arms of the lever 7 are disposed at an angle of less than 180° with respect to each other. This angularity is best illustrated in Figures 1 to 3, and its purpose will presently appear, as the description proceeds. It is not intended to limit the application of the invention to any particular angle of deviation between the extension 8 and the end portion 9, but the best results have been obtained by using approximately the angular deflection illustrated. In determining the proper angle between arms 8 and 9 the prime consideration is that arm 8 shall assume a rest position 25 in over center relation to the bearing 6 when the door is in the open position of Figure 1, and that arm 9 shall assume a rest position in over center relation to the bearing 6 when the door is in the closed position of Figure 2.

The chain 12 is attached by any suitable adjustable means to the end portion 9 of the lever arm 7. The chain 12 secures one end of the spring 13 which is attached at its other end to the bracket 14 on the lower portion of the door frame.

The pivot and spring mechanism are the same on both sides of the door opening.

As illustrated in Figure 1, the downward inclination of the track 3 is sufficient to bring the door 2 to rest in a substantially horizontal position parallel with the ceiling 15, thus allowing a maximum of clearance under the open door. The downward inclination of the track 3 also causes the door to tend to stay in opened position when it has been moved to that position. It is noted also in Figure 1 that when the door is in opened position the extension 8 on the lever arm 7 has swung to an over center position and is no longer vertical, whereby the weight of the lower portion of the door tends to rotate the lever arm 7 in a counter-clockwise direction, thereby also exerting a force tending to keep the door in fully opened position. The desired angularity of the extension 8 in the opened position of the door is determined by the angular relationship of the extension 8 with respect to the end portion 9 and should be such that extension 8 assumes substantially the position illustrated when the end portion 9 is directed downwardly in substantially vertical position by the tension of spring 13.

To close the door from the position shown in Figure 1, it is necessary to exert an outward pull on the door to raise the extension 8 over its top dead center, whereupon the door will swing outwardly and downwardly, assuming the position shown in Figure 3. As the extension 8 turns in a clockwise direction, as viewed in Figures 1 and 3, the increasing mechanical advantage of the spring 13 on the end portion 9 will effectively counterbalance the weight of that part of the door supported by the extension 8. By appropriately shifting the means of attachment of the chain 12 to the end portion 9, and adjusting the spring to the proper tension, a counterbalancing effect may be obtained which will substantially balance the weight of the door throughout the whole course of its travel from opened position to closed position, and vice versa. As the extension 8 continues to rotate clockwise during the closing of the door, the end portion 9 rotates into an over center position, as shown in Figure 2. As soon as the line of tension of spring 13 passes the axis of the bearing 6, the tension of the spring acting through the end portion 9 tends to keep the door in the fully closed position. This is an important consideration to prevent looseness and rattling such as may be caused by the wind. Although the door is held in closed position by the spring 13, such holding force is relatively small and may easily be overcome by an outward pull on the lower portion of the door. As soon as the door has been slightly opened, the line of tension of the spring 13 will have again passed to the left of bearing 6, as viewed in Figure 2, and the spring from that point on will exert its force in a direction tending to assist in opening the door by counterbalancing the weight thereof.

A mechanical feature of importance in the above described operating mechanism is the particular construction of the lever arm 7 and bearing 6. As illustrated in Figure 6, the bearing 6 is made large to distribute the wear and guide the journal portion of the lever arm 7 without looseness. To add rigidity, the oppositely directed arms on the lever 7, and the central journal portion of the lever 7, are formed integrally from a single rod, so that one arm bearing the extension 8 lies on one side of the bearing 6 and the end portion 9 lies on the other side of the bearing 6. This construction balances the forces on the lever

arm and contributes in obtaining a proper fit for the door which will not vary through continued use.

We deem ourselves entitled to all uses, modifications and variations of the preferred embodiment as fall within the spirit and scope of the appended claims.

Having now described our invention and in what manner the same may be used, what we claim as new and desire to protect by Letters Patent is:

1. In an overhead door, a door frame for said door, a pair of tracks extending from adjacent the upper portion of said door frame, supporting means on the upper end of said door carried by said tracks, a lever pivotally mounted intermediate its ends on each side of said frame, one arm of said lever being pivotally attached to the lower portion of said door, the other arm of said lever being attached to a tension means, said two arms of said lever being disposed at an angle of substantially less than 180°, the angle between said arms being such that when said door is open the door carrying arm of said lever will be disposed in an over center position beyond the vertical, and when said door is closed said tensioned arm will be disposed in an over center position beyond the vertical, whereby said door will tend to remain in either fully opened or fully closed position, and will be substantially counterbalanced in intermediate positions.
2. In an overhead door adapted to assume a vertical position when closed and an elevated, substantially horizontal position when open, guide means for carrying the upper end of said door in a substantially horizontal path, a lever pivoted at either side of said door and having a door supporting arm pivotally connected to the lower portion of said door so that when said door is in fully opened position said arm is in an over center position beyond the vertical, and a tension means acting on an arm of said lever to counterbalance the weight of the door in intermediate positions, said two arms of said lever being disposed at an angle of substantially less than 180°, said tension means assuming an over center position with respect to the pivot point of said lever when said door is fully closed, whereby when said door is fully opened it tends to remain open, and when said door is fully closed it tends to remain closed.
3. In an overhead door of the type adapted to assume a vertical position when closed and a horizontal position when open, a tensioned lever means for supporting a portion of said door, said lever being thrown to an over center position beyond the vertical when said door is open whereby the weight of said door tends to hold it open, the tensioning means on said lever being thrown to an over center position when said door is closed to hold it closed, said tensioning means counterbalancing the weight of the door in intermediate positions.
4. In an operating mechanism for an overhead door of the type which assumes a vertical position when closed and an overhead horizontal position when open, a bearing adapted to be secured to a door frame, a unitary operating lever having one end thereof pivotally connected to a bottom portion of said door, said lever extending through said bearing and terminating in an arm, and spring tensioning means attached to said arm to counterbalance said door, said arm being formed on said lever at an angle of substantially less than 180° so that the closing movement of

said door will cause said spring tensioning means to pass over center with respect to said bearing thereby yieldably holding said door in fully closed position.

5. In an overhead door of the type adapted to assume an elevated, substantially horizontal position when open, a guide means for carrying the top of said door in a path inclined slightly downwardly from the horizontal as said door is moved to open position, and a lever pivoted at one side of said door for carrying a bottom portion of said door, said lever being pivotally attached to said door so that when said door is in fully opened position said lever will assume an over center position beyond the vertical thereby tending to retain said door in said fully opened position. 10

6. In an overhead door, a guide means to carry the top of said door in a substantially horizontal path of travel; a lever having a bearing interme-

15 diate its ends; said lever having a door supporting arm pivotally connected to a lower portion of said door, an offset portion forming a journal in said bearing, and a second arm having a tension means applied thereto; said second arm deviating angularly from the direction of said door supporting arm substantially less than 180° ; and said two arms and offset portion being formed integrally.

7. In a door operating mechanism, a bearing adapted to be secured to a door frame, a unitary operating lever comprising a door operating arm, a spring operated arm offset from and at an angle of substantially less than 180° to said door operating arm, and an offset portion integrally connecting said arms and forming a journal therefor in said bearing.
